UNITED STATES PATENT OFFICE.

ARTHUR W. CASH, OF DECATUR, ILLINOIS, ASSIGNOR TO H. MUELLER MANUFACTURING CO., OF DECATUR, ILLINOIS, A CORPORATION OF ILLINOIS.

REGULATOR FOR ANESTHETIC APPARATUS.

1,216,285.

Specification of Letters Patent. Patented Feb. 20, 1917.

Application filed August 12, 1915. Serial No. 45,182.

To all whom it may concern:

Be it known that I, ARTHUR W. CASH, a citizen of the United States, residing at Decatur, in the county of Macon and State of Illinois, have invented new and useful Improvements in Regulators for Anesthetic Apparatus, of which the following is a specification.

The present invention relates to apparatus for administering anesthetics, and has for its object to effect the automatic control and regulation of the flow of the anesthetic from the tank or carboy, in which such gases are usually sold commercially, to the container with which the inhaler of the apparatus is connected.

In apparatus of this type it is customary to deliver the gas, either nitrous oxid or oxygen, for example, or a mixture of the two, from the tanks or carboys to a distensible or expandable container, sometimes in the form of a bag, and from such bag deliver the gases in suitable quantities to the inhaler. The gas in the tanks or carboys being under very high pressure, while that in the container, from which the nozzle of the inhaler draws its supply, is at a lower pressure, suitable reducing instrumentalities may be provided if necessary between the carboy and the container.

My present invention contemplates the utilization of the distensible or expandable container as a regulating means for the flow of gas from the carboy to such container, so that when the apparatus has been once set for a certain pressure in the container an automatic control is effected by the movements of the container as it expands and collapses, which will maintain always the same pressure from the tank or carboy into the container, provision being made also whereby this may be varied to suit the needs of the work and the container pressure regulated at will.

In order that the invention may be clear to those skilled in the art, I have shown in the accompanying drawings one embodiment of my invention, although it will be understood that this illustration, and the following description, is in no sense restrictive, as it is obvious that mechanical expedients other than those herein disclosed may

be utilized in working out my invention without departing from the principle thereof.

In the drawings:—

Figure 1 is a perspective view of an apparatus with which my invention may be used.

Fig. 2 is a side elevation of my regulating device.

Fig. 3 is a top plan view of the regulator shown in Fig. 2.

Fig. 4 is a cross sectional view on substantially the line 4—4 of Fig. 2.

Fig. 5 is a vertical sectional view of the regulator.

Fig. 6 is a side elevation, partly in section.

Fig. 7 is a sectional view on substantially the line 7—7 of Fig. 5.

Fig. 8 is a view showing the mounting of one of the operating levers for the regulator.

Fig. 9 is a perspective view of the operating lever.

Fig. 10 is a sectional view of the double check valve between the carboys and a container.

Referring to the drawings by numerals, like numbers indicating like parts in the several views, 10 (Fig. 1) indicates any suitable support or standard for the apparatus, carrying at its upper end a frame comprising a central controller 11, which may be of any suitable design and structure, from which controller a plurality of inlet pipes 12 branch, and outlet pipes (one being shown) 13 leading to any suitable inhaler as 14. The pipes 12 leading from the controller communicate with containers 15, these containers being shown in the present instance as expandable bags, two being shown, although it is obvious that any number necessary or desired may be used.

The container 15 will ordinarily be connected with the carboys 16 and 17 in any suitable manner, as for example by the pipes 18, it being customary in certain classes of work to have two carboys, one containing nitrous oxid, and the other containing oxygen, so that either one or the other, or a mixture of the two, can be utilized, the gases being delivered from the carboys 16 and 17 to the container 15, from which they are

emitted by the pipes 12 to the controller 11 where they are commingled, and thence by the outlet pipes 13 and inhaler 14 to the patient. The carboys may be conveniently carried by the cross arms 19 supported, as shown, on the pipe 12 adjacent the controller, and will be provided with the usual outlet valves 20, as shown.

- The pipes 18 deliver to the head 21 of the 10 regulator, which head is screw-threaded or otherwise hermetically secured to a depending pipe or nipple at the end of the arm 12, the gas from the pipes 18 delivering, as shown in the present embodiment, at the opposite sides of a T-shaped head 22, the leg of which is screwed into the head 21 and delivers by passage 23 through a valve seat at the lower end of the head 21. The T-shaped head 22 is preferably provided with 15 the non-return check valves 24, as shown in Fig. 10, these valves being normally held in the position shown by the spring 25, which spring will yield and permit the valves to open under pressure coming from the carboys 16 and 17, but will close the nipples of the inlet pipes 18 under back pressure through the T-head.

The passage 23 delivers to a valve seat 26 formed in a recess in the lower part of 30 the head 21, within which recess is located a spring valve 27, the spring 28 of which bears against a diaphragm cup or casing 29, which is connected with the head 21 by means of the diaphragm 30, the outer edge 35 of which is clamped between the two-part casing 29, as shown in Figs. 5 and 6, the inner edge of the ring-shaped diaphragm being clamped between a flange 31 formed at the lower end of the head 21 and a clamping ring 32, as shown. It will be seen that the diaphragm does not really function as the ordinary diaphragm, but forms a yielding connection between the head 21 and the casing 29, so as to permit of relative movement thereof, and, furthermore, it serves to seal the chamber 33 in the diaphragm casing against the escape of gases coming through the port 26 past the valve 27 from the passage 23. The valve 27 is formed as 40 45 50 shown in Fig. 7, so as to permit free passage of the gas coming through the port 26 past the valve into the chamber 33.

The casing 29 is provided at its lower end with the nipple 34 which screws into, or is 55 otherwise secured to the collapsible container 15, said nipple 34 being provided with any desired number of passages 35 through which, as will be apparent, the gas delivered from the carboys to the T-head 22 past the valves 27 will go to the container 15.

The regulator head 21 is provided with a screw-threaded section, as best shown in Fig. 5, on which is adjustably mounted a ring 36 provided with a flange 37. The said 60 65 ring 36 may be adjusted upwardly or down-

wardly on the head 21 throughout the length of the screw-threaded section, and as a convenient adjusting means I have shown in the present instance a ring cap 38 which fits over the upper end of the ring 36, and is secured thereto in any suitable manner, as by screws 39, which screws enter any one of a series of threaded holes 40 formed in the upper face of the ring 36, so that adjustment of the cap ring 38 with respect to the ring 36 may be made, and the cap ring properly positioned. The said cap ring is provided with an operating handle 41, and an index or pointer 42, which registers with a series of indicating marks on the exterior 80 of the regulator head 21 (see Fig. 2), which indicating marks or graduations denote the delivery pressure in the container, and serve as a setting means for the regulator.

Pivottally mounted on the diaphragm cap 85 or casing 29 are a series of levers 43, the ends of which bear upon the flange 37 of the ring 36, and as these levers are tilted from the position shown in Fig. 5 to that shown in Fig. 6, they bring about a relative movement between the regulator head 21 and the casing 29, this being permitted by the loose diaphragm connection between the parts, thus permitting, in the position shown in Fig. 5, the valve 27 to open more or less 90 under the pressure coming from the carboys through the passage 23 to the port 26, or as shown in Fig. 6 closing the valve tightly so as to prevent the passage of the gas to the container 15.

In order that the operation of the levers 43 will be automatic and directly controlled by the condition of the container 15, the levers 43 are provided with depending arms 44 which, as shown in Fig. 1, extend downwardly adjacent the container 15, said arms 44 preferably having the finger pieces or plates 45 at their lower ends to engage the container 15. As the container distends it will be obvious the arms 44 will be thrown outwardly, as shown in Fig. 6, and the levers 43 will cause a relative movement of the regulator head 21 and diaphragm casing 29, tending to close the valve 27 and prevent the flow of gas from the carboys to the distended container.

In this position of regulator the gas may be withdrawn from the container at the lower pressure, and will pass by way of passages 35 in the nipple 34 past the valve 27, and by passages 45 to the pipe 12 and the controller 11, from which in regulated pressure it will go to the inhaler 14.

As the container 15 collapses on the drawing out of the gas the arms 44 will fall, decreasing the power exerted on the levers 43, and releasing the valve 27 to permit the entrance of more gas from the carboys.

It will be seen that an automatic and very close regulation can thus be effected, the 130

regulator after having once been set operating to admit a certain pressure of gas to the container, which pressure will be maintained automatically as the container 15 collapses or distends.

While the levers 43 with their operating arms 44 may be mounted in any convenient manner, I have shown in the present construction a simple and convenient mounting, and one which lends itself to easy assemblage of the levers and the diaphragm casing. In this construction I provide the undercut ring 46 at the top of the diaphragm casing, having the cutaway seats 47 to receive the levers 43, said levers being provided at their inner ends with the journals 48 which lie within the undercut ring, as shown in Fig. 4, and permit the free rocking movement of the levers.

From the foregoing it will be seen that a regulating device for apparatus of this kind, which will closely and automatically control the charging of the container, is provided, and one which is made up of few parts, which parts may be cheaply constructed and readily assembled, and, furthermore, that the instrumentalities are so combined as that likelihood of derangement of the parts or undue wearing thereof is practically eliminated.

I claim:—

1. Pressure regulating means comprising relatively movable members having fluid passages therethrough, a valve to control flow through said passages, and automatic means to move said members relative to each other to govern the range of movement of said valve.

2. Pressure regulating means comprising relatively movable members having fluid passages therethrough, a yielding connection between said members, a valve to control flow through said passages, and automatic means to move said members relative to each other to govern the range of movement of said valve.

3. Pressure regulating means comprising relatively movable members having fluid passages therethrough, a yielding diaphragm connecting said members, a valve to control flow through said passages, and automatic means to move said members relative to each other to govern the range of movement of said valve.

4. Pressure regulating means comprising relatively movable members having fluid passages therethrough, a valve to control flow through said passages, and levers carried by one of said members to effect a relative movement of said members and govern the range of movement of said valve.

5. Pressure regulating means comprising a fixed member having fluid passages therethrough, a movable member having fluid passages therethrough connected with said

fixed member, a valve to control flow through said passages, and lever mechanism carried by one of said members to effect a relative movement of said members to govern the range of movement of said valve.

6. Pressure regulating means comprising a fixed member having fluid passages therethrough, a movable member having fluid passages therethrough connected with said fixed member, a valve to control flow through said passages, and adjustable automatic means to move said members relative to each other to govern the range of movement of said valve.

7. Pressure regulating means comprising relatively movable members having fluid passages therethrough, a valve to control flow through said passages, an expanding container to which one of said members delivers, and means operated by said container to move said members relative to each other to govern the range of movement of said valve.

8. Pressure regulating means comprising relatively movable members having fluid passages therethrough, a valve to control flow through said passages, an expanding container to which one of said members delivers, and lever mechanism operated by said container to move said members relative to each other to govern the range of movement of said valve.

9. Pressure regulating means comprising relatively movable members having fluid passages therethrough, a valve to control flow through said passages, an expanding container to which one of said members delivers, and levers carried by one of said members and operated by said container to move said members relative to each other to govern the range of movement of said valve.

10. Pressure regulating means comprising relatively movable members having fluid passages therethrough, a valve to control flow through said passages, a distensible container to which one of said members delivers, and levers engaging said distensible container to effect movement between said members and govern the range of movement of said valve as said container expands and collapses.

11. In a fluid pressure regulator, and in combination, a member having a fluid-receiving and a fluid-discharging passage therethrough, a valve controlling said fluid-receiving passage, a chambered member with which said valve member is movably connected having fluid passages therethrough, levers mounted on said chambered member and engaging said valve member, and means for automatically operating said levers to effect a relative movement of said valve and chambered member and govern the range of movement of said valve.

12. In a fluid pressure regulator, and in

- combination, a member having a fluid-receiving passage and a fluid-discharging passage therethrough, a valve seat at the lower end of said member, a valve in operative relation to said seat, a chambered member having a fluid passage therethrough, a flexible diaphragm connecting said valved member and said chambered member, levers mounted on said chambered member and adjustably engaged with said valved member, and means for automatically operating said levers to effect relative movement between said members and govern the range of movement of said valve.
13. In a fluid pressure regulator, and in combination, a member having a fluid-receiving passage and a fluid-discharging passage therethrough, a valve seat at the lower end of said member, a valve mounted therein, a chambered member on which said valve rests having a fluid passage therethrough, a flexible diaphragm connecting said members and sealing said chamber, an adjustable ring on said valved member, levers mounted on said chambered member and engaging said adjustable ring, and means for automatically operating said levers to effect relative movement between said members and govern the range of movement of said valve.
14. In a fluid pressure regulator, and in combination, a member having a fluid-receiving passage and a fluid-discharging passage therethrough, a valve seat at the lower end of said member, a valve mounted therein, a chambered member on which said valve rests having a fluid passage therethrough, a flexible diaphragm connecting said members and sealing said chamber, an adjustable ring on said valved member, a cap ring adjustably mounted on said first named ring and having an index finger to register with an index on said valved member, levers mounted on said chambered member and engaging said adjustable ring, and means for automatically operating said levers to effect relative movement between said members and govern the range of movement of said valve.
15. In a fluid pressure regulator, and in combination, two members having fluid passages therethrough and so connected as to permit relative movement, a valve between said members controlling a fluid passage, means for automatically effecting relative movement of said members to govern the range of movement of said valve, adjustable means for controlling the extent of movement of the members, and index means for setting said adjustable means.
16. In a fluid pressure regulator, and in combination, a member having a fluid-receiving passage and a fluid-discharging passage therethrough, a second member having a fluid passage therethrough and connected for relative movement with said first named member, a valve between said members, automatically operated lever mechanism for effecting relative movement of said members to govern the range of movement of said valve, and a flanged ring adjustably mounted on said first named member and engaged by said lever mechanism, and an index member adjustably mounted on said flanged ring.
17. In a fluid pressure regulator, and in combination, a member having a fluid receiving passage and a fluid-discharging passage therethrough, a two-part chambered member surrounding said first named member, a valve between said members, a diaphragm clamped between the parts of said chambered member, means for connecting said first named member to said diaphragm centrally thereof, a flanged ring adjustably mounted on said first named member, levers pivoted on said chambered member and engaging at their inner ends said flanged ring, and a distensible container to operate said levers and effect a relative movement between said members to govern the range of movement of said valve.
18. In a fluid pressure regulator, and in combination, a member having fluid passages therethrough, a valved chamber in its lower end, a valve in said chamber controlling a fluid passage, a chambered member in which the valved end of said first named member is seated having fluid passages therethrough, a flexible diaphragm coupling said members and permitting relative movement thereof, a flanged ring adjustably threaded to said first named member, lever seats formed on the top of said chambered member, levers mounted in said seats and engaging said adjustable ring, and fluid pressure actuated means to operate said levers to effect relative movement of said members and govern the range of movement of said valve.
19. In a fluid pressure regulator, and in combination, a fluid pressure receiving and delivering member, a second fluid pressure receiving and delivering member inevitably connected with said first named member, a valve between said members governed by the relative movements thereof, an expandible container to which said regulator delivers, and lever mechanism operated by said expandible container to effect relative movement of said members.
20. In a fluid-pressure regulator, and in combination, a member having a fluid-receiving passage, and a fluid discharge therethrough, a valve seat at the lower end of said member, a valve in operative relation to said seat, a chambered member having a fluid passage therethrough, a spring contacting with said valve and said chambered member, a flexible diaphragm, contacting

with said valve member and said chambered member, levers mounted on the chambered member and adjustably engaged with the valve member, and means for automatically operating said levers to effect relative movement between said members and govern the range of movement of said valve.

21. In a fluid pressure regulator, and in combination, a member having a fluid-receiving passage, and a fluid-discharging passage therethrough, a valve seat at the lower end of said member, a valve mounted therein, means connected to said valve to cushion its contact with the end of the fluid-discharge passage, a chambered member on which said valve rests having a fluid passage therethrough, a flexible diaphragm connecting said chambered member and the first-mentioned member and sealing said chamber, an adjustable ring on said valve member, levers mounted on said chambered member and engaging said adjustable ring and means for automatically operating said levers to effect relative movement between said members and govern the range of movement of said valve.

22. In a fluid-pressure regulator, and in combination, a member leading from the supply carboys, a one-way valve in the member, a second member connected to the first having a fluid-receiving passage and a fluid-discharge passage therethrough, a third member having a fluid passage therethrough and connected for relative movement with said second-named member, a valve between the second and third members, and automatically operated lever mechanism for effecting relative movement of said second and third members to govern the range of movement of said valve.

23. In a fluid-pressure regulator, the combination of a supporting stand, carboys supported on said stand, pressure-regulating

means connected to said carboys, members operable by pressure for actuating the pressure regulating means, a mixing chamber for the fluids delivered from the carboys, and a delivery tube leading from the mixing chamber.

24. In a fluid-pressure regulator, the combination of a supporting stand, a mixing chamber on said stand, a delivery tube leading from the mixing chamber, pipes leading from the mixing chamber, supports on said pipes, carboys detachably supported on said supports, pressure-regulating means connected to said pipe, and means for controlling said regulating means.

25. In a fluid-pressure regulator, the combination of a supporting stand, carboys supported on said stand, pressure-regulating means connected to said carboys, members operable by pressure for actuating the pressure regulating means, a mixing chamber for the fluids delivered from the carboys, a controller on said mixing chamber, and a delivery tube leading from the mixing chamber.

26. In a fluid-pressure regulator, the combination of a supporting stand, a mixing chamber on said stand, a controller on said mixing chamber, a delivery tube leading from the mixing chamber, pipes leading from the mixing chamber, supports on said pipes, carboys detachably supported on said supports, pressure-regulating means connected to said pipe, and means for controlling said regulating means.

In testimony whereof I have hereunto set my hand in presence of two subscribing witnesses.

ARTHUR W. CASH.
